UNITED STATES PATENT OFFICE

ALEXANDER O. HOLVERSON, OF NEW YORK, N. Y.; MARY ALINE HOLVERSON, OF NEW YORK, N. Y., EXECUTRIX OF SAID ALEXANDER O. HOLVERSON, DECEASED.

DETACHABLE CUFF.

1,097,024.

Specification of Letters Patent. Patented May 19, 1914.

Application filed October 27, 1911. Serial No. 657,173

To all whom it may concern:

Be it known that I, ALEXANDER OSCAR HOLVERSON, a citizen of the United States, residing at New York, county of New York, and State of New York, have invented certain new and useful Improvements in Detachable Cuffs, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein-

Figure 1 of the drawings is a view in perspective of my improved detachable cuff attached to a shirt-sleeve. Fig. 2 is a section of the same taken on the broken line 2--2 in Fig. 1, longitudinally of the sleeve through the cuff-link or button. Fig. 3 is a cross-section of the same taken transversely of the sleeve through the cuff-link or button. Fig. 4 is a plan view of the cuff detached and laid out flat.

The principal object of the invention is to provide a detachable cuff which when buttoned or linked upon the wristband of a shirt-sleeve will substantially cover and conceal from view the wristband, and prevent the wristband from drawing away from or out of proper position relatively to said cuff.

Other objects will appear in connection with the following description.

In carrying out my invention I employ a fold-cuff of the style generally known as a French cuff, and adapt the same to receive between its folds the wristband of a shirt-sleeve, each fold of the cuff being provided with buttonholes, all of which buttonholes are adapted to register with the buttonholes in the wristband; and the cuff when buttoned or linked upon the wristband being adapted to grip and hold the wristband within the fold of the cuff at points diametrically opposite the link or button.

Referring to the drawings wherein the invention is shown in preferred form, the shirt-sleeve, 1, has upon its lower end a wristband, 2, formed and provided with end-buttonholes, 3, in the usual manner.

My improved cuff is made of double width,

and is adapted to be folded along its longitudinal middle line, 4, to the form shown in Figs. 1 and 2; 5, being the outer member and, 6, the inner member thereof. The outer member, 5, is provided with buttonholes, 7, near its opposite ends, and the inner member, 6, is provided with correspondingly located buttonholes, 8, adapted to register with the respective buttonholes, 7, when the cuff is folded, all of said buttonholes, 7 and 8, being adapted to register with one another when the cuff is folded and bent into form for use, as shown in Figs. 1 and 3. The folded cuff is adapted to receive between its outer and inner members, 5 and 6, the wristband, 2, of the shirt-sleeve, as shown in Fig. 2, the relative lengths of the cuff and wristband being such that when the wristband has been inserted within the folded cuff, and the cuff and wristband bent to the form shown in Figs. 1 and 3, the buttonholes, 8, in the wristband will register with the registering buttonholes, 7 and 8, in the cuff, all of said buttonholes being adapted to receive the same cuff-link or button 9. The ends of the cuff-members, 5 and 6, extend somewhat farther outside of the buttonholes than do the ends of the wristband, so that when the cuff and wristband are buttoned together as shown in Figs. 1 and 3, the wristband will be practically concealed from view by the projecting ends of the cuff-members.

The cuff may be made of any desired width, and both members, 5 and 6, are preferably made of substantially the same width, and of a considerably greater width than the wristband.

The ends of the inner member, 6, of the cuff are preferably slightly tapered as shown at, 10, whereby they project less, and are less conspicuous, than the ends of the outer member, 5, when the cuff is in use.

My improved cuff is preferably made to fold upon a substantially straight line, that is, having little or no spring or flare between the members when the cuff is folded. By making the cuff to fold upon a substantially straight line, the inner and outer members of the cuff, when folded and bent into form for use, will be forced into close proximity to each other so as to forcibly engage and grip between them the interposed wristband, and thus serve to effectively hold the wristband in proper position within the folded cuff. The cuff being adapted to be folded

upon a substantially straight line, its outer and inner members, 5 and 6, may be made integral with each other if desired, as shown in Figs. 1 and 2, or the members may be 5 made separate from each other and attached together by means of a longitudinal seam, 11, which will determine the fold line.

A cuff made and attached to the wristband of a shirt-sleeve as described, will so 10 grip and hold the wristband that for all practical purposes the wristband and cuff will be held in the same relative positions in use as though they were permanently connected together.

15 The drawings are to some extent diagrammatic, in that no attempt has been made to show the several plies of fabric whereby the cuff and wristband are formed. It will be understood, however, that the cuff and 20 wristband may be formed of as many thicknesses or plies of fabric as desired, the plies

being secured together in the usual manner.

What I claim as new and desire to secure by Letters Patent is—

A laundried fold cuff of the class described, comprising inner and outer members adapted to embrace between them the usual shirt-wristband, each of said members provided with wholly inclosed buttonholes 30 registering with one another and with buttonholes in said wristband, whereby the ends of the cuff-members and wristband are adapted to be held in substantially fixed relation to each other by the usual cuff-buttons. 35

In testimony whereof, I have hereunto set my hand this 21st day of October, 1911.

ALEXANDER O. HOLVERSON.
